CLAIM

The ornamental design for a shoe upper, as shown and described.

DESCRIPTION

FIG. 1 is a perspective view of a preferred embodiment of a shoe upper in accordance with my new design;

FIG. 2 is a left side elevational view thereof;

FIG. 3 is a top plan view thereof;

FIG. 4 is a right side elevational view thereof;

FIG. 5 is a front elevational view thereof; and,

FIG. 6 is a rear elevational view thereof.

Broken lines in the figures are for illustrative purposes only and form no part of the claimed design.

1 Claim, 3 Drawing Sheets Fig. 2.

Fig. 3.
